UNITED STATES PATENT OFFICE.

DAVID W. ELIAS, OF HAYWARD, CALIFORNIA.

SHOE.

Application filed March 16, 1922. Serial No. 544,082.

To all whom it may concern:

Be it known that I, DAVID W. ELIAS, a citizen of the United States, residing at Hayward, in the county of Alameda and State of California, have invented certain new and useful Improvements in Shoes, of which the following is a specification.

My invention is a shoe constructed without lacings or buttons which may be put on the foot and quickly closed and secured on the foot.

Referring to the annexed drawing in which my invention is illustrated and which forms a part of this specification:

15 Figure 1 is a side elevation of the outer side of my shoe in closed position.

Figure 2 is a view similar to Fig. 1 in open position.

Figure 3 is a fragmentary side view of 20 the upper part of the outer side of my shoe.

Figure 4 is a horizontal section of the upper part of the shoe in closed position taken on line 4—4 of Figure 1.

In the drawing 1 indicates the sole, 2 the heel, and 3 the upper of my shoe, the upper being separated at the front and formed with a front flap 4, like a buttoned shoe, to close the separation when the shoe is put on, said flap extending from the inner side of 25 the upper part of the upper across the front and around the upper part of the outer side of the upper.

A leather lining 5 is secured inside of the upper part of the upper 4, and a strap 6, 35 secured at its inner end to the inside of flap 4 extends from said flap through a slot 7 in the forward part of the outer side of the upper, and between said outer side, the back and the inner side of the upper and said lining, out through a slot 8 in said inner side and around the outside of the flap 4 and the outside of the outer side of the upper. The inner end of the strap 6 is substantially as wide as the height of the flap and is secured 40 to the inside of said flap with its upper edge coincident with the upper edge of said flap. The strap converges from its inner end for a distance of about half its length to a point 9 of the strap located within the inner side 45 of the upper, and said converging part of the strap is split lengthwise in three places by slots 10, 11 and 12, forming four spaced strap members 13, 14, 15 and 16, the strap member 13 being at the upper edge of said part, 50 converging part of the strap, the strap member 16 being at the lower edge of said part,

and the strap members 14 and 15 being between the strap members 13 and 16. The outer side of the upper rearwardly from the slot 7 is stitched to the lining 5 by rows of stitching 17, 18 and 19 respectively through the slots 10, 11 and 12, forming guideways 20, 21, 22 and 23 respectively for the strap members 13, 14, 15 and 16. A buckle 24 is secured to the outer side of the upper near the back thereof for buckling the outer end of the strap when the strap and upper are drawn around the ankle and the flap 4 closed over the forward part of the outer side of the upper as shown in Figure 1. The strap being of such width at its inner end that it is secured to flap 4 substantially the entire height of the flap, and being split into four strap members 13-16, and the guideways 20-23 being provided for guiding said strap members, enables the flap to be drawn at every point snugly around the ankle quickly by a single strap and thus makes it possible to put on and take off the shoe more quickly than it is possible to put on or take off a lace 80 or button shoe, while at the same time providing a shoe of neat appearance. Buttons 25 may be secured to the outside of the flap 4 near its outer edge to give the shoe the appearance of a buttoned shoe. 85

Having described my invention, I claim:

1. In a shoe, an upper formed with a front separation and a front flap in the manner of a button shoe, a strap secured at its inner end to the inside of said flap, a lining 90 secured to the inside of said upper, the outer side of said upper having a slot through which said strap extends from said upper, the strap then extending between the outer side, the back and the inner side and said lining, out through a slot provided in the inner side of the upper, and around the outside of said flap and outer side wall, and a buckle on the outer side of the upper to which the outer end of the strap is buckled. 95

2. In a shoe, an upper formed with a front separation and a front flap in the manner of a button shoe, a strap secured at its inner end to the inside of said flap, a lining secured to the inside of said upper, the outer side of said upper having a slot through which said strap extends from said upper, the strap then extending between the outer side, the back and the inner side and said lining, out through a slot provided in the inner side of the upper, and around the outside of said flap and outer side wall, and a 100

105

110

buckle on the outer side of the upper to which the outer end of the strap is buckled, the inner end of said strap being substantially as wide as the height of the flap so that it is attached to the flap substantially its height to draw the flap at every point snugly around the ankle.

3. In a shoe, an upper formed with a front separation and a front flap in the manner of a button shoe, a strap secured at its inner end to the inside of said flap, a lining secured to the inside of said upper, the outer side of said upper having a slot through which said strap extends from said upper, the strap then extending between the outer side, the back and the inner side and said lining, out through a slot provided in the inner side of the upper, and around the outside of said flap and outer side wall, and a buckle on the outer side of the upper to which the outer end of the strap is buckled, the inner end of said strap being substantially as wide as the height of the flap so that it is secured to the flap substantially its height, said strap being split from its inner end for a certain distance into a plurality of strap members.

4. In a shoe, an upper formed with a front separation and a front flap in the manner of a button shoe, a strap secured at its inner end to the inside of said flap, a lining secured to the inside of said upper, the outer side of said upper having a slot through which said strap extends from said upper, the strap then extending between the outer side, the back and the inner side and said lining, out through a slot provided in the inner side of the upper, and around the outside of said flap and outer side wall, and a buckle on the outer side of the upper to which the outer end of the strap is buckled, the inner end of said strap being substantially as wide as the height of the flap so that it is secured to the flap substantially its height, said strap being split from its inner end for a certain distance into a plurality of strap members, and said outer side of the upper being stitched to the lining through the splits in said strap for a short distance rearwardly from the slot in said outer side, forming guideways for said strap members.

In testimony whereof I affix my signature.

DAVID W. ELIAS.
